By George W. Bly

United States Patent Office.

HORACE C. WILCOX, OF WEST MERIDEN, CONNECTICUT, ASSIGNOR TO
THE MERIDEN BRITANNIA COMPANY, OF SAME PLACE.

Design No. 4,247, dated July 19, 1870.

DESIGN FOR A TEA OR COFFEE-POT.

The Schedule referred to in these Letters Patent and making part of the same.

all whom it may concern:

Be it known that I, HORACE C. WILCOX, of West Meriden, county of New Haven and State of Connecticut, have invented or discovered a certain new and useful Design for a Tea or Coffee-Set, which I will proceed to describe, referring to the drawings, in which the same letters indicate like parts.

In the accompanying photographic drawings—

a is the body of the vessel.

b are the handles.

c, the nozzle.

d, the cover.

e, the supporting-legs, the whole combined and con-

figurated so as to produce a new and rich design for a tea or coffee-set.

I believe that by the accompanying photographic drawings and description I have shown the nature and construction of this invention.

What I claim, and desire to secure by Letters Patent, is—

The design of a tea or coffee-set, &c., substantially as shown and described.

H. C. WILCOX. [L. S.]
